Primary Examiner — R. Johnson(74) *Attorney, Agent, or Firm* — Ellenoff Grossman & Schole LLP; James M. Smedley; Alex Korona(57) **CLAIM**

We claim the ornamental design for a snare device, as shown and described.

DESCRIPTION

FIG. 1 is a top perspective view of a snare device embodying my new design;

FIG. 2 is a top plan view thereof;

FIG. 3 is a bottom plan view thereof;

FIG. 4 is a front view thereof; and,

FIG. 5 is a back view thereof.

The broken lines in the drawings are for the purpose of illustrating unclaimed portions of the snare device and form no part of the claimed design.
